SHIPPING CONTAINER FOR HUMAN REMAINS

Howard B. Holman and William M. Holman, both of
2610 SE Hawthorne Blvd., Portland, Oreg. 97214

Filed Sept. 19, 1968, Ser. No. 13,612

Term of patent 14 years

Int. Cl. D31

U.S. Cl. D19—1

FIG. 1

FIG. 2

FIG. 3

FIG. 4

FIGURE 1 is a top plan view of a shipping container for human remains showing our new design with the cover removed.

FIGURE 2 is a longitudinal sectional elevational view taken along the line 2—2 of FIGURE 1.

FIGURE 3 is a side elevational view of FIGURE 1 with the cover in place, and

FIGURE 4 is a typical elevational view of either end of FIGURE 3.

We claim:

The ornamental design for a shipping container for human remains, substantially as shown and described.
